UNITED STATES PATENT OFFICE

CLARENCE G. JOHNSON, OF HARTFORD CITY, INDIANA

WINDOW SEALING CONSTRUCTION

Application filed November 26, 1928. Serial No. 321,861.

The present invention pertains to a novel window sealing construction, and the principal object is to provide a device wherein the window is automatically and effectively sealed against the weather at all times.

This object is accomplished essentially by constructing the parting strip in the nature of an expandible member including two parts running longitudinally of the window frame. At least one of these parts is slideable in the frame towards one of the sashes which it engages, and between the parts is provided spring means so that said slideable part is constantly pressed against the corresponding sash.

The invention is fully disclosed by way of example in the following description and in the accompanying drawing, in which—

Figure 1 is a vertical section of a window constructed according to the invention;

Fig. 2 is a fragmentary front elevation of the window, partly in section;

Fig. 3 is a horizontal section thereof, showing one of the sashes raised or lowered;

Fig. 4 is a fragmentary elevation of the parting strip, partly in section;

Fig. 5 is a transverse section thereof;

Fig. 6 is a transverse section and a fragmentary side elevation of a modified form of parting strip;

Fig. 7 is a fragmentary side elevation of another modification;

Fig. 8 is a transverse section thereof; and

Fig. 9 is a transverse section of still another modification.

Reference to these views will now be made by use of like characters which are employed to designate corresponding parts throughout.

In Figures 1, 2 and 3 is illustrated a window frame 1 of usual construction having a pair of sliding sashes 2 and 3 mounted therein. The parting strips between the sashes are of a special formation whereby they have a sealing effect on the respective sashes. In

Figures 1 to 5 for example the parting strip consists of a pair of channel members 4 and 5, the latter of which is received within the former. It will be seen in Figure 1 that the parting strip is divided midway between its ends as at 6 in order to provide two separate

and independent assemblies for a purpose which will presently appear.

The backs of the channel members 4 and 5 are opposed to one another, and the back of the outer channel 4 is arranged to engage the upper or lower sash as the case may be. The sides of the inner member 5 are formed with apertures 7, while the sides of the channel 4 are formed with slots 8 adjacent the apertures. Springs 9 are mounted in and between the channel members and are seated by means of lugs 10 struck inwardly from the backs of the channels.

Fastening nails or screws 11 driven through the apertures 7 and slots 8 hold the inner channel member in a fixed position against the side of the window frame, while the outer channel member 4 is slideable relatively to the inner channel by reason of the slots 8. The springs 9 consequently press the channel member 4 against the sash which is engaged thereby. The two assemblies above and below the parting line 6 are reversed with respect to each other, so that the slideable channel of the lower assembly engages the lower sash 2 while the sliding channel of the upper assembly moves in the opposite direction and engages the upper sash 3.

In the construction shown in Figure 6 there is a parting strip proper of T-shaped cross section and designated by the numeral 15. Sealing strips 16 are inserted beneath the head of the strip 15 and in parallel relation to the stem 17. The stem is formed with a transverse bore 18 in which is received a spring 19 which bears against both strips 16. This form of the device therefore expands in both directions and acts on both sashes if either one is raised or lowered. A covering strip 20 is laid across the base of the stem 17 and over the exposed edges of the strips 16, and the assembly is secured to the side of the window frame by nails or screws 21 driven through the strip 20 and stem 17.

In the embodiment shown in Figures 7 and 8 the parting strip consists of two channel members 25 placed back to back and held in this relation by studs 26. These studs are headed at both ends and further serve to hold bow springs 27 in each channel. The

channels are secured to the side of the window frame by tacks 28 driven through one side of each. In the channels are slidably fitted sealing strips 29 engaging the free ends of the springs 27 and notched at 30 to accommodate the heads of the members 28. This device also acts in both directions, by reason of the provision of two strips 29, in the manner described in connection with Figure 6.

10 In Figure 9 is illustrated a one-piece all-metal parting strip having a box-like formation 31 of rectangular cross section with one end embedded in the side 32 of the window frame. At the median of the opposite side 15 the metal is bent in at 33 and drawn out at 34, in duplicate fashion, so that it may be bent as at 35 over each of the adjacent corners of the formation 31 to bring the free ends 36 of the metal into engagement with 20 the sashes 37. The spring action is provided by the band portions 34-36 which obviously act in both directions in the same manner as the devices shown in Figures 6, 7 and 8.

25 Although specific embodiments of the invention have been illustrated and described, it will be understood that various alterations in the details of construction may be made without departing from the scope of the invention as indicated by the appended claims.

30 What I claim is:

1. In a window, a frame, a pair of sashes slidably mounted therein, a parting strip between said sashes, said parting strip comprising a pair of longitudinal, unitary, U-shaped 35 channel members one within the other and relatively slidable, and spring means between said parts for moving one of said parts into spring pressed engagement with one of said sashes.

10 2. In a window, a frame, a pair of sashes slidably mounted therein, a parting strip between said sashes, said parting strip comprising a pair of longitudinal, unitary, U-shaped channel members one within the other, one 45 of said parts being fixed to said frame and the other part being slidably mounted with respect to said first named part, and spring means between said parts for moving said slidable part into spring pressed engagement 50 with one of said sashes.

3. In a window, a frame, a pair of sashes slidably mounted therein, a parting strip between said sashes, said parting strip comprising a pair of longitudinal, unitary, U-shaped 55 channel members one within the other, one of said parts being fixed to said frame and the other part being slidably mounted with respect to said first named part, and springs between said parts for moving said slidable part into spring pressed engagement with one of said sashes.

4. In a window, a frame, a sash slidably mounted therein, a parting strip adjacent said sash, said parting strip comprising a pair 60 of longitudinal channel members one within

the other and relatively slidable, one of said members being fixed to said frame and the other engaging said sash, lugs struck inwardly from the backs of the channels, and coil springs disposed within said members and having their ends mounted over opposed lugs of opposed channel backs.

5. In a window, a frame, a pair of sashes slidably mounted therein, a parting strip between said sashes, said parting strip comprising a pair of longitudinal channel members one within the other, said strip being severed substantially midway between its ends to form two distinct parting strip assemblies, one of the channel members of each assembly 75 being secured to said frame and the other member being slidable relatively thereto and engaging the adjacent sash, and spring means disposed between said channel members and tending to move the movable members against 80 said sashes.

90 In testimony whereof I affix my signature.
CLARENCE G. JOHNSON.
